UNITED STATES PATENT OFFICE

2,605,938

VALVED DROP FORMING STOPPER

Vojtěch Balcar, Prague-Smichov, Czechoslovakia

Application December 13, 1946, Serial No. 716,057

3 Claims. (Cl. 222—422)

1

The object of invention is a closure or stopper, which makes it possible to empty the contents of a bottle in drops or in a continuous stream and makes possible measuring of great accuracy. There are similar arrangements e. g. stoppers grounded in the neck of the bottle wherein the measuring mechanism is partly in the stopper and partly in the neck of the bottle. But these stoppers have the following great disadvantage.

As the stopper is placed in the neck of the bottle, the axis of the stopper coincides with the axis of the neck and so it is possible that when the bottle is tilted which is done to a great extent when measuring doses, the stopper falls out of the bottle.

The object of invention is a dripping stopper, which solves and eliminates this disadvantage in a simple and original way. It makes an accurate dosing in drops or the letting out of a stream of liquid possible.

In the drawings which illustrate a preferred stopper construction embodying the invention, Fig. 1 is a view in vertical central section, and Fig. 2 is a view of the stopper in top plan with a portion of the upper end of the stopper body broken away to show a featured detail.

Referring now to the drawings, the body 1 of the stopper includes a lower cupped portion screw threaded at 1a for screw threaded engagement upon the neck of the bottle (not shown) the contents of which are to be dispensed by gravity flow principles, and an upper solid cylindrical portion 1b having a diametral tapered bore 1c extending transversely therethrough. A pair of spaced passages 1d, 1e extend longitudinally through central section 1f of the stopper body from bore 1c to the screw-threaded interior 1g.

A tapered plug 3 having a ground-in fit with bore 1c and rotatable about its longitudinal axis is provided with an axial passage 3a extending from the dispensing end 3b of the plug which communicates with a transverse passage 3c leading to the exterior of the plug. Another axial passage 3d extends from the opposite end 3e of the plug and communicates with a second transverse passage 3f in the plug leading to the exterior thereof at its side.

Intermediate the two passageways 3a, 3d, the plug 3 is provided with a peripheral groove 3g for receiving a ball type detent 4 that is urged into groove 3g by spring 5, the ball 4, spring 5 and plug 6 to retain spring 5 in place being received in a transverse bore 1h in the stopper body that extends from its outer surface to the bore 1c in alignment with groove 3g in the plug. Thus, plug 3 is free to rotate on its axis, but endwise

displacement thereof in bore 1c is resisted by the coaction of the detent ball 4 and groove 3g.

Transverse passages 3c, 3f in plug 3 are so aligned with respect to passages 1d, 1e in the stopper body that when plug 3 is fully inserted in the bore 1c, passage 3c will communicate with passage 1d, and passage 3f will communicate with passage 1e when the parts are in the positions shown in Fig. 2. Rotation of plug 3 either way a few degrees from the position shown will however bring the exterior surface of the plug over the upper ends of passages 1d, 1e closing off the latter.

End 3e of plug 3 is enlarged to provide easier turning with the fingers and contains a socket threaded at 3h for receiving a threaded air adjusting screw 7. The base of socket 3g is tapered at 3i to match a complementary taper 7a at the inner end of screw 7 so that when the latter is screwed in or out of the socket, the spacing between the two tapered surfaces 3i, 7a decreases or increases, respectively.

Screw 7 is also provided with a passageway 7b offset from the screw axis and extending longitudinally from tapered end 7a to the opposite end surface of the plug, i. e. to atmosphere. Passage 3d in plug 3 leads to the tapered base 3i of the socket.

The manner of operation of the improved stopper is believed to be self-evident from the drawings but a brief summary will be conducive to a clear understanding of the invention.

The liquid contents of the bottle cannot be delivered by gravity flow through outlet passage 3a unless air is admitted into the bottle to replace the liquid discharged. Hence by the simple expedient of adjusting the rate at which air is admitted into the bottle through the stopper, the rate at which the contents are delivered through outlet 3a will likewise be adjusted.

Control over the rate of air admission is obtained by manipulating screw 7. With the end 7a seated firmly against the tapered surface 3i, this being a ground fit, the inner end of passage 7b is blocked off and no air can get through from atmosphere to the interior 1g of the stopper and hence also the interior of the bottle. However by backing off a turn or so on screw 7, a small space is established between the tapered surfaces 7a, 3i, thus allowing air to enter at a very low rate through passageways 7b, 3d, 3f and 1e which permits the contents of the bottle to be discharged through passages 1d, 3c and 3a in a droplike manner at a corresponding low rate, making it easy to measure the number of drops dispensed. The discharge rate can be increased

3

by backing off the adjusting screw 7 still further thus increasing the drop rate until substantially a condition of continuous flow obtains.

The stopper is "closed" by screwing down on screw 7 until the tapered surfaces 1a, 3i meet thus blocking off all admission of air through the seriatly arranged air inlet passages. The stopper can also be "closed" by slight rotation of plug 3. This not only blocks off the air inlet at passage 1e but also the fluid outlet at passage 1d.

Having now particularly described and ascertained the nature of my said invention and in what manner the same is to be performed, I declare that what I claim is:

1. A dropper closure for bottles comprising a body portion having a transverse open-ended bore extending therethrough, spaced passages extending through the body from the inner surface of the closure to said bore, a rotary plug extending through said bore having a liquid outlet passage extending from one end thereof to communicate with one of the passages through the body in one position of rotation of the plug, said plug having a threaded socket at the other end thereof having a seating surface at the bottom thereof and a passageway leading axially from the bottom of said socket to communicate with the other passage through the body in the aforesaid position of rotation of the plug and an adjusting screw in said socket having a seating surface at the inner end thereof complementary to the seating surface at the bottom of the socket and having an air inlet passage opening on said seating surface spaced from the axial center thereof.

2. A dispensing closure for bottles comprising a body portion having a transverse open-ended tapered bore extending therethrough, a pair of spaced passages extending through the body from the inner surface of the closure to said bore, a tapered rotary plug extending through said bore having a liquid outlet passage extending from the small end thereof to communicate with one of said passages through the body in one position of rotation of the plug, a threaded socket in the larger end of the plug having a conical bottom seating surface and an air passage leading axially from the conical bottom to communicate with the other passage through the body in the aforesaid position of rotation of the plug and an air inlet shut off and adjusting screw threaded into said socket having a conical end

4

seating surface adapted for sealing engagement with the conical bottom of the socket and an eccentrically disposed air passage extending from said conical end surface to the outer end thereof.

3. A dispensing closure for bottles comprising a body portion having a transverse open-ended tapered bore extending therethrough, a pair of spaced passages extending through the body from the inner surface of the closure to said bore, a tapered rotary plug extending through said bore having a liquid outlet passage extending from the small end thereof to communicate with one of said passages through the body in one position of rotation of the plug, a threaded socket in the larger end of the plug having a conical bottom seating surface and an air passage leading axially from the conical bottom to communicate with the other passage through the body in the aforesaid position of rotation of the plug, an air inlet shut off and adjusting screw threaded into said socket having a conical end seating surface adapted for sealing engagement with the conical bottom of the socket and an eccentrically disposed air passage extending from said conical end surface to the outer end thereof and means for retaining said plug from endwise movement in and from said bore including an annular groove in the surface of said plug and a spring pressed detent carried by the body portion engaged in said groove.
